UNITED STATES PATENT OFFICE.

WILLIAM G. JENSEN AND KRESTEN R. JENSEN, OF NOWATA, OKLAHOMA.

PUMP JACK.

Application filed March 1, 1926. Serial No. 91,594.

This invention relates to an improvement in pump jacks of the type forming the subject-matter of Patent No. 1,415,937.

The object of the present invention is to provide a pump jack which has all of the advantages of the type forming the subject-matter of the prior patent referred to and which also eliminates vibration which has advantageous counterbalancing features and which is of strong and durable construction, reliable and effective in operation, and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a perspective view showing one embodiment of the invention.

Figure 2 is a view partly in vertical longitudinal section and partly in side elevation, and

Figure 3 is a fragmentary view in transverse vertical section taken approximately on the line 3-3 of Figure 2.

Referring to the drawings it will be seen that the pump jack includes a stationary frame, designated generally at 1 and having base bars 2, vertical standards 3 and inclined braces 4 connecting the base bars and the vertical standards. The standards 3 and brace bars 4 are held in transversely spaced relation by means of spacing members 3^a and 4^a. The base bars 2 are secured to the lower ends of the standards 3 at one end and at the lower end of the braces 4 at their other ends. The upper ends of the standards 3 and braces 4 are suitably secured together. The base bars 2 are maintained in spaced relation by means of transversely extending members 6 which have their upper surfaces hollowed out to provide bearings 7 for purposes which will hereinafter more clearly appear. A walking beam, designated generally at 10, is provided and is made up of a pair of channel iron members 11 fastened together in spaced relation. The walking beam 10 is fulcrumed intermediate its ends on the upper end of a pivot post or support 12. The post 12 includes a pair of members 13 connected at their lower ends by a hollow supporting shaft 14 which is rotatable on the

bearing surface 7 of one of the spacing members 6. The hollow supporting shaft 14 of the pivoted support is held on its bearing surface 7 by means of a pivot bolt 14^a extended through the supporting shaft and through the vertical flanges of the base bars 2 of the stationary frame. At their upper ends the members 13 are connected by a top piece 15 and also have transversely aligned apertured ears 16 through which a pivot bolt 17 is extended. The pivot bolt 17 is also extended through the opening 18 of a supporting or fulcrum block 19 which is positioned between the members 11 of the walking beam and fastened thereto, as indicated at 20. As shown in Figure 2 the top piece 15 is hollowed out to provide a bearing cavity 15^a in which the lower rounded end of the fulcrum block 19 is fitted.

With the arrangement described the walking beam is mounted for rocking or oscillating movement on the pivoted slot but due to the fact that the support is pivoted the walking beam may move bodily in such manner as to cause the end thereof connected with the polish rod to move in a substantially straight line. In order to constrain the walking beam to proper movement to effect the purpose just stated, a pair of links 25 are provided between the walking beam and the stationary frame 1. One end of each link 25 is pivotally connected to the upper end of the stationary frame and the other end of each link is pivotally connected to the walking beam. As shown in the drawings, the ends of the links 25 which are connected to the main frame are so connected by means of bolts and nuts 26 whereas the opposite ends of the links are connected by bolts and nuts 27 to the channel members 11 of the walking beam 10. As illustrated in Fig. 3 the links 25 are properly bent to offset their ends in the necessary manner.

As indicated, one end of the walking beam 100 is connected to the polish rod P and the opposite end of the walking beam is provided with a bearing 30 adapted to receive a counterbalance or weight 31 which makes the entire assembly easy and smooth in operation and entirely devoid of vibration.

Means is provided for imparting rocking motion to the walking beam and this means includes a rocking frame, designated generally at 35, and including a pair of converging base members 36 fastened, as at 37, to lugs 38 provided on a hollow rock shaft 39

and secured at their other ends to a pivot block 40. A yoke-shaped frame member 41 is provided and has the lower ends of its arms 42 also fastened to the lugs 38. The 5 body portion 43 of the yoke frame member 41 is spanned by brace members 44 which extend down and are connected to the converging ends of the base members 36. With this arrangement the advantages of a truss 10 are obtained in the rocking frame. The rocking frame is mounted for rocking movement on the stationary frame by means of its hollow rock shaft 39 which has a working fit on the bearing surface 7 of one of the cross members 6 as shown in Fig. 2 and 15 which is held in such position by means of a pivot bolt 45. The pivot block 40 is provided with spaced and apertured ears 46 which receive between them the apertured 20 cross head 47 provided at the lower end of a connecting rod 48. The connecting rod 48 is provided at its upper end with a second cross head 49 having aligned and apertured ears 50 co-acting with a pivot bolt 51 to 25 connect the cross head 49 to a pivot block 52 fastened, as at 50, to the channel members 11 of the walking beam and having a rounded portion 54 at its lower end rotatably fitted in a bearing surface 55 provided 30 therefor on the head 51. As shown in Figure 2 the lower head 46 is rotatably fitted on a similar bearing surface 46^a provided in the pivot block 40^a.

The yoke member 41 is extended above 35 its connection with the brace members 44 and is provided with a series of transverse grooves 60 whereby the rocking frame may be adjustably connected to the shackle rod

lines 61 to vary the stroke of the polish rod.

With this arrangement when the outer 40 end of the walking beam is swung upwardly or downwardly the horizontal component of its movement is compensated by the pivotal movement of its support and thereby true rectilinear movement is imparted 45 to the polish rod. Along with these advantages the pump jack has all of the features of ruggedness and strength required in actual practice.

We claim:

1. A pump jack having a stationary frame provided with transversely extending bearing members having bearing recesses, a pivoted support having a hollow shaft in its lower end engaging the recesses of one of the bearing members, means for holding said shaft engaged with its bearing recess, a walking beam fulcrumed on the upper end of the pivotal support, links between the walking beam and the main frame for constraining the walking beam to proper movement, means for rocking the walking beam including a rocking beam having a shaft rotatably mounted in the recess of one of the bearing members, and a connection between the rocking frame and the walking beam.

2. A pump jack having a walking beam, means for rocking the same including a rocking frame made up of converging base 70 bars, a rock shaft having lugs connected to the bars at one end, a yoke member connected to said lugs, and inclined bars between the yoke and the base bars.
